CIRCUIT INTERRUPTER

Benjamin P. Baker, Turtle Creek, and Andrew H. Bakken, Edgewood, Pa., assignors to Westinghouse Electric & Manufacturing Company, East Pittsburgh, Pa., a corporation of Pennsylvania

Application October 27, 1938, Serial No. 237,264

22 Claims. (Cl. 200—150)

This invention relates to high-voltage high-power circuit breakers and more particularly to improvements in the circuit interrupting elements therefor.

5 In the application of B. P. Baker, Serial No. 230,946, filed September 21, 1938, and assigned to the assignee of this application, is disclosed a circuit breaker of the high-voltage high-power type in which circuit interruption is accomplished by two or more serially connected circuit interrupting elements. Each of the interrupting elements shown and described in the aforesaid application consists of a cylindrical casing approximately one-half of which is utilized to support a corrugated wall arc chamber, whereas the other half serves as an expansion chamber into which arc gases are discharged.

10 A stationary contact assembly is provided in each expansion chamber consisting of a plurality of contact fingers, the contact surfaces of which terminate adjacent the open end of the arc chamber and are adapted to cooperate with a ring contact carried by a movable operating member passing axially through both interrupting elements. The movable contact ring is adapted to be brought into sliding contacting engagement with the contact surfaces of the stationary contact fingers during the closing operation of the breaker. We have discovered that in the event 15 of appreciable misalignment of the moving and fixed contacts as well as burning and pitting of the beveled leading edges of these contacts, the movable contact sometimes positively engages the leading tips of the stationary contact fingers and 20 prevents the moving contact from sliding into its final contacting position.

It is an object of our invention to provide a contact structure for circuit breakers of the foregoing type which is freely movable to the closed 25 circuit position even though the stationary and movable contacts are out of alignment or become pitted from arcing as a result of repeated circuit opening operations.

30 A further and more specific object of our invention is the provision of a contact structure of the tulip type for circuit breakers in which provision is made for moving the stationary contact fingers laterally at right angles to the movement of the moving contact in response to a positive engagement of the moving contact with the stationary contact fingers during the closing stroke of the breaker so as to permit the moving contact to slide unopposed into final contacting engagement with the stationary contact fingers.

35 In circuit breakers of the type shown and de-

scribed in the aforesaid application, which are capable of interrupting a large number of volts per inch of contact separation, it is desirable and advisable to frequently flush the interrupting elements with clean arc extinguishing liquid so as to prevent carbonized products of decomposition of the liquid from forming a conducting film upon the insulating surfaces of the arc extinguishing structure. Frequent flushing of the arc extinguishing devices is of particular importance in 10 circuit breaker structures of the type wherein the arc extinguishing devices have a relatively small capacity for retaining arc extinguishing liquid.

15 A further object of our invention is to provide flushing means for the interrupting elements of circuit breakers of the high-voltage type whereby the arc extinguishing structure is subjected to the flow of clean arc extinguishing liquid following each circuit interrupting operation.

20 Another object of our invention is the provision of a flushing device for circuit interrupting elements which is self-contained in the interrupting unit and actuated by the same resilient means used for moving the movable contact mechanism to the open circuit position.

25 Still another object of our invention is the provision of a high-power circuit breaker having a main operating spring for moving the movable contact assembly to the open circuit position, which spring is also employed for actuating a 30 flushing device for the arc extinguishing elements after each circuit opening operation and which is further used for controlling the release of pressure within the interrupter housing.

35 Other objects and advantages relate to details of our circuit breaker structure and to the arrangement of the various parts thereof, all of which will appear more fully in the following description when read in connection with the accompanying drawings, in which:

Referring to the drawings, the reference number 15 designates a metal casing having an upper support plate 17 which carries a hollow insulator 19 of weatherproof material, such as porcelain or the like. Upon the upper end of the insulator 19 is seated an annular plate 21

30 which carries a metallic dome-shaped closure 23. The hollow insulator 19 is maintained in position by a tubular strain member 25, preferably of insulating material, which is secured at its lower end to the support plate 17 and at its 35 upper end to an annular plate 27 which, in turn, is bolted to the annular plate 21.

The metallic casing 15, the insulator 19, in conjunction with the tubular strain member 25, and the upper closure 23, provide a housing which 40 is adapted to be filled with arc extinguishing liquid and in which a circuit interrupting unit 29 is immersed. The circuit interrupting unit 29 comprises two interrupting elements 31 and 33 joined by a flanged casing 35. A second flanged 45 casing 37 is secured to the upper end of the interrupting element 31 and is provided with a plurality of, in this instance, four laterally extending support arms 39. The support arms 39 are releasably secured to the annular plate 27 and serve as the sole support for the interrupting 50 unit 29 within the breaker housing.

The interrupting elements 31 and 33 each consists of a tubular casing member 41 of insulating material, the ends of which are provided with 55 suitable metallic collars 43 to which the respective flanged casings 35 and 37 may be secured. Disposed within the casing 41 are a plurality of washers 45 and 47 of insulating material of different internal diameter alternately disposed in 60 stacked relation so as to provide an arc chamber 48 having corrugated wall surfaces. The space above the washers 45 and 47, as defined by the casing 41 and the flange member 37, constitutes an expansion chamber 49 in which arc 65 gases may be discharged and in which the stationary contact assembly of each interrupting element is adapted to be housed. This stationary contact assembly, as shown in Figs. 2 to 5, inclusive, consists of a plurality of contact fingers 70 51 disposed in substantially parallel relation with respect to each other and supported by a generally tubular support member 53. The support member 53 has an outwardly extending flange 55 which is adapted to be clamped between the 75 flanged casing member 37 and the upper collar

43 of the interrupting element 31. In the interrupting element 33, the flange 55 is clamped between the flanged casing 35 and the upper collar 43 of that element.

Each of the contact fingers 51 of the interrupting element 31 is connected by means of a flexible shunt 57 to the flanged casing 37. The moving contact assembly comprises an operating member 59 extending axially through the arc chambers 48 and the expansion chambers 49. 10 This member carries a contact ring 61 having outwardly extending contact surfaces 63 thereon which are adapted to make sliding contact-engagement with the contact fingers 51.

Disposed immediately above the contact ring 15 61 are a plurality of washers 65 and 67 of insulating material and of different external diameter alternately arranged in stacked relation so as to form a corrugated piston member 69, which is adapted to be moved with the contact ring 61 20 into the arc chamber 48 during the opening movement of the interrupter. The washers 65 have an outside diameter with respect to the inside diameter of the washers 45, such that when the piston member 69 has been moved into the 25 arc chamber 48, the piston member confines and limits the arc chamber to a narrow elongated passage of relatively small cross section.

The left-hand contact surface 63 of the contact ring 61, as viewed in Fig. 2, has considerably 30 greater length than the remaining contact surfaces, so as to cause the left-hand contact surface to separate last in the point of time from the left-hand contact finger 51 to insure drawing the arc within the elongated arc passage 35 formed between the stationary washers 45 and 47 and the piston member 69. The piston member 69 during its movement to the open circuit position displaces arc extinguishing liquid from the arc chamber 48 longitudinally of the arc 40 stream and assists in expelling arc gases from the arc chamber 48 into the expansion chamber 49.

The interrupting element 33 is generally similar in construction to the construction of the 45 element 31 except that the flexible shunts 51 of the element 33 are connected to a tubular sleeve 71 carried by the operating member 59. The tubular sleeve 71 is of metallic material and is connected electrically with the contact ring 61 50 of the interrupting element 31, thereby providing a series electrical connection between the two interrupting elements.

The contact ring 61 for the interrupting element 33 engages a metallic cap member 73 secured to the lower end of the operating member 59, which cap member engages a plunger member 75 (Fig. 1) supported by a suitable straight-line operating mechanism generally indicated at 77 in Fig. 1. The plunger member 75 is connected by a flexible shunt 79 to a terminal 81 extending through the side of the casing 15. A second line terminal 83 is provided which extends through the side of the closure member 23 and is connected by a flexible connector 85 65 to the flanged casing 37. Thus, the electrical circuit through the circuit breaker proceeds from the line terminal 83, connector 85, casing 37, flexible shunts 51, contact fingers 51, contact ring 61, metallic sleeve 71, to the flexible shunts 51 (not 70 shown) of the interrupting element 33 through the interrupting element 33 in a similar manner, as described in connection with interrupting element 31. From the contact ring 61 of the interrupting element 33, the circuit proceeds 75

to the cap member 13, the plunger member 75, flexible connector 79, and terminates at the line terminal 81.

The operating mechanism 71 is utilized primarily to move the operating member 59 and its associated parts to the closed circuit position. The movement of the operating member 59 to the open circuit position is accomplished by means of a battery of compression springs 87 located within the dome-like enclosure 23 and disposed between two movable pressure plates 89 and 91. The pressure plate 91 is secured to the upper end of the operating member 59, as shown in Figs. 1 and 2, and directly transmits the force from the springs 87 to the operating member to move it to the open circuit position when released by the straight-line operating mechanism 71.

The leading tips of the contact surfaces 63 are rounded so as to normally permit the contact ring 61 to slide into contacting engagement with the contact surfaces of the contact fingers. In the event that the contact fingers and the contact ring become greatly out of alignment, or in the event that the leading tips become deeply pitted or burned so as to destroy the rounded edges, the contact rings 61 will not slide freely to their final closed circuit position, but will jam so as to prevent free closing unless provision is made to prevent the contact fingers from making positive engagement with the moving contact rings.

As more clearly shown in Figs. 3 to 5, we have provided an arrangement for supporting the contact fingers 51 with respect to the support casting 53 so that when the contact fingers make positive engagement with the contact ring 61 during the closing movement, the contact fingers will be carried a short distance with the contact ring. This longitudinal movement of the contact fingers 51 is utilized to cause a lateral movement of the fingers at right angles to the path of movement of the contact ring 61 so as to release the positive engagement between the contact fingers and the contact ring, thereby permitting the ring to slide freely to its fully closed position. To accomplish the foregoing, the contact fingers 51 are disposed about the outer circumference of the cylindrical support casting 53, and extend upwardly through a rectangular aperture 93 formed in the flange 55 which serves as a guide to prevent lateral movement circumferentially of the casting 53. Further guide means are provided by outwardly projecting bosses 95 formed at the lower end of the cylindrical casting 53. Thus, it will be seen that the apertures 93 and the bosses 95 permit lateral movement of the contact fingers 51 in a direction radially of the cylindrical casting 53. The upper end of each contact finger 51 is provided with two laterally extending projections 97, as shown in Figs. 3 and 5. The projections 97 are disposed between the flange 55, which supports the cylindrical casting 53, and a second outwardly extending flange 99 located at the upper end of the cylindrical casting 53. The upper flange 99 is spaced some distance above the support flange 55 so as to permit a limited amount of longitudinal movement of the contact finger 51 with respect to the cylindrical support casting 53.

Each of the contact fingers 51 is provided with a cam surface 101 which is adapted to engage a similar cam surface 103 disposed at the lower edge of the casting 53 so as to cooperate with the corresponding cam surface on the contact finger. A plurality of coil springs 105, in this instance two, encircle the contact fingers 51 so as to bias

them towards the support casting 53 and also bias them into engagement with the contact rings 61 when the interrupter is in the closed circuit position.

As shown in Figs. 2 to 5, inclusive, it will be apparent that the cam surfaces 101 and 103 are such that in the event that the contact fingers 51 are moved upwardly by the positive engagement with the contact ring 61, the contact fingers 51 will be moved outwardly, thus releasing the positive engagement between the contact fingers and the contact ring so as to permit the contact ring to move to its final contacting position. The lower biasing spring 105 is alternately looped on top of a boss 107, secured to each contact finger 51, and below a similar boss 109, secured to the outer circumference of the support casting 53, as more clearly shown in Fig. 5. It will thus be seen that the lower spring 105 also biases the contact fingers 51 downwardly so that upon following a disengagement of the contact fingers from the moving contact ring, as a result of longitudinal movement upwardly of the contact fingers, the contact fingers will again be moved downwardly to their normal position so as to insure a spring pressed engagement with the contact ring.

The main operating springs are also utilized in controlling the release of pressure within the housing during and following circuit interruption. The arrangement whereby this is accomplished is set forth in detail in the application of A. H. Bakken, Serial No. 230,948, filed September 21, 1938, now Patent No. 2,199,607, issued May 7, 1940, and assigned to the assignee of the instant application.

As set forth in the aforesaid application of A. H. Bakken, the movable pressure plates 89 and 91 are provided with four apertures 111 and 113, respectively, through which four guide and support rods 115 extend. Each guide and support rod 115 is secured at its lower end to a respective support arm 39. The upper end of the guide rods 115 are united with a stop plate 117 against which the movable pressure plate 89 is normally urged by the operating springs 87. To the upper side of the stop plate 117 is secured an upstanding box-like support 119 each of the four sides of which is provided with a rectangular aperture 121 for the reception of a simple lever arm 123. The inner ends of the four lever arms 123 are adapted to rest upon the shoulder 125 of a square headed bolt 127, the upper end of which extends through a metallic bushing 129 (Fig. 1) of the dome-like closure 23. The outer ends of the levers 123 make pivotal contact with adjustable screws 131 carried by the moving pressure plate 89. The dome-like closure 23 preferably comprises a lower cylindrical section 133 and an upper cap member 135, which cap is releasably seated upon the cylindrical section 133. The bolt 127 is provided with a nut 137 for placing the bolt in tension so as to draw the head thereof towards the bushing 129 in the cap 135 which at the same time raises the levers 123 so that they fulcrum about the upper edges of the rectangular apertures 121 in the box-like support 119 and produce a downward force at their outer ends acting upon the adjustable screws 131 and consequently act to move the pressure plate 89 downwardly against the springs 87. It clearly follows that the springs 87 apply a biasing force through the movable pressure plate 89, the levers 123 and the bolt 127 to yieldingly maintain the cap 135 in position. It is also apparent that the

existence of pressure, within the breaker housing of a predetermined value, will cause the cap member 135 to be lifted against the action of the main operating springs 87 so as to permit the pressure to be relieved within the interrupter housing.

The main operating springs 87 are also utilized to actuate a liquid pumping device for flushing the arc chambers 48 following each circuit interrupting operation. The liquid circulating device and the manner of its association with the main operating spring will now be described. The flanged casing 37 is provided with a cover plate 139 which has an upstanding collar 141 through which the upper end of the operating member 59 extends and is guided during its reciprocating movement. Movable about the upstanding collar 141 is a cylinder 143 having the side wall 145 (Figs. 7 and 9) slidably engaging the outer circumference of the cover plate 139. The movable cylinder 143 has four outwardly projecting ears 147 provided with suitable apertures through which the guide rods 115 extend and maintain the cylinder in proper alignment during its reciprocating movement. A coil spring 149 encircling each guide rod 115 and disposed between a support arm 39 and an ear 147 normally maintains the cylinder 143 in the upward position so as to provide an annular chamber 151. Liquid is admitted into the chamber 151 by a simple valve arrangement comprising an annular channel 153 machined in the lower side of the cylinder 143, which channel communicates with the liquid above the cylinder through a plurality of apertures 155, as more clearly shown in Fig. 8. The apertures 155 are normally open but are adapted to be sealed during the downward stroke of the cylinder 143 by a floating annularly-shaped valve member 157 slidably supported on pins 159.

The cylindrical chamber 151 communicates with the arc chambers 48 of the interrupting elements 31 and 33 by means of conduits 161 and 163, respectively. Details of the passage 45 from the cylindrical chamber 151 to the respective conduits 161 and 163 are more clearly shown in Figs. 2 and 7. The cover plate 139 is provided with an aperture 165 which registers with a passage 167 provided in the flange casing member 37. The passage 167 is also provided with a ball spring pressed check valve 169 for preventing the reverse flow of arc extinguishing liquid into the chamber 151. The passages 167 in the flanged casing member 37 terminate in an opening 171 below the check valve 169, which openings register, respectively, with the conduits 161 and 163. The lower ends of the conduits 161 and 163 are provided with suitable fittings for joining the conduits to the lower collars 43 of 60 the interrupting elements 31 and 33, respectively. The collars 43 are provided with radially extending passages 173, as shown in Figs. 10 to 13, inclusive. The passages 173 terminate in an annular channel 175 at the base of the respective 65 arc chambers 48. It will thus be seen that as the cylinder 143 is moved downwardly, the liquid therein will be forced through the passages 167 past the check valve 169, through the conduits 161 and 163, through the passages 173 and into 70 the annular channels 175 and then upwardly through the arc chambers 48 in the direction shown by the arrows in Figs. 11 and 13. Movement of arc extinguishing liquid through the arc chambers 48 in this manner following each 75 circuit interrupting operation flushes out the

arc chambers 48 removing products of decomposition produced by the arc acting upon the liquid during arc extinction and thereby prevents the settling of the solid products upon the insulating surfaces of the arc chamber which would impair the insulating qualities thereof.

As heretofore stated, the movable cylinder 143 is maintained in its raised or uppermost position by the springs 149. Movement in the downward direction so as to cause a discharge of liquid from the chamber 151 is produced by auxiliary spring means which are charged during the opening stroke of the operating member 59 by direct action of the main operating springs 87. More specifically, the movable cylinder 143 is provided with a plurality of, in this instance four, tubular guides 177 secured about the outer periphery thereof, being open at the top and closed at the bottom except for an aperture through which an operating bolt 179 extends. An auxiliary operating spring 181 encircling the bolt 179 and disposed within the tubular spring guide 177 normally maintains the bolt 179 in its uppermost position. The movable pressure plate 91, which directly actuates the operating member 59, is provided with four outwardly extending ears 183 which register with the heads of the bolts 179 so that when the pressure plate 91 is moved downwardly, the ears 183 engage the bolts 179 and compress the springs 181 prior to 30 the time the pressure plate 91 reaches its lowermost or full open position.

The combined tension of the springs 181 is less than the tension of the main operating springs 87, which makes compression of the 35 springs 181 possible by means of the main operating springs 87. Thus, the movable cylinder 143 is rendered operative during the opening movement of the operating member 59 by the direct action of the main operating springs 87. 40 The cylinder 143, however, is not moved downwardly to discharge the liquid contained within the chamber 151 until the pressure within the arc chambers 48 of the interrupting elements 31 and 33 has been reduced to a predetermined 45 value, such as will permit the springs 181 to move the cylinder 143. In other words, the main operating springs 87 merely place the moving cylinder 143 in readiness so that when suitable pressure conditions exist within the arc 50 chamber following arc extinction, the cylinder becomes effective to force clean arc extinguishing liquid through the arc chambers to rid them of any deleterious substances. This arrangement for actuating the movable cylinder 143 permits movement of the operating member 59 and consequently the movable contact ring 61 to the full open position independently of the pressure conditions within the arc chamber set up by the respective arcs, which pressures may, in the absence 55 of the particular arrangement, tend to stop the movement of the operating member to the open position.

The springs 149 which retract the movable cylinder 143 are, of course, more readily compressible than the auxiliary operating springs 181, so as to permit the springs 181 to operate the cylinder 143 against the action of the springs 149. Upon movement of the operating member 59 and the pressure plate 91 to the closed circuit 65 position, the springs 149 retract the cylinder 143, causing it to fill with fresh arc extinguishing liquid through the valve openings 155, and place the cylinder in readiness for the next circuit 70 opening operation. 75

The downward movement of the movable pressure plate 91 and its directly connected operating member 59 is limited by a stop plate 185 threaded to the upper end of the upstanding collar 141. In order to absorb the shock of suddenly stopping the downward movement of the pressure plate 91, a buffer plate 187 is disposed immediately above the stop plate 185 and is normally held in spaced relation with respect to the stop plate 185 by a relatively weak coil spring 189 encircling the upper end of the operating member 59.

This spacing provides a layer of liquid between the plates 185 and 187 which must be displaced when the pressure plate 91 strikes the buffer plate 187, thereby producing the desired buffer action to arrest motion of the operating member of the breaker without shock to the mechanism. In order to prevent high resistance to the movement of the pressure plate 91 through the arc extinguishing liquid, the latter is preferably perforated, as shown in Fig. 8, which necessitates the use of the buffer plate 187 to obtain the requisite resistance to movement at or near the end of the opening stroke of the operating member 59. It will, of course, be understood that if the movable pressure plate 91 is imperforated, the same buffering action may be obtained without the use of the buffering plate 187.

Although we have shown and described a specific circuit breaker structure, it is to be understood that the same is for the purpose of illustration and that changes and modifications may be made by those skilled in the art without departing from the spirit and scope of the appended claims.

We claim as our invention:

1. In a circuit interrupter, a pair of separable contacts at least one of which is movable, said contacts having slidably engageable surfaces parallel to the general direction of movement of said movable contact, and means cooperating with said other contact for moving said other contact laterally in a direction away from said movable contact in response to longitudinal movement by said movable contact during the closing movement of said contacts to cause said surfaces of said contacts to be brought into alignment.

2. In a circuit interrupter, a pair of separable contacts, at least one of which is movable, said contacts having engageable surfaces parallel to the general direction of movement of said movable contact, means normally applying a biasing force at right angles to said contact surfaces for holding said surfaces in engagement, and means supporting said other contact for limited movement both laterally and longitudinally of the path of movement of said movable contact, and means operative in response to longitudinal movement of said other contact by said movable contact to move said other contact laterally against the bias of said biasing means to cause said contact surfaces to be moved into cooperative engagement.

3. In a circuit interrupter, a support, a contact finger yieldingly held by said support, a moving contact adapted to make sliding contact longitudinally of said contact finger, and cooperating cam means carried by said support and said contact finger for moving said contact finger laterally in a direction away from the path of movement of said moving contact in response to longitudinal movement of said contact finger with respect to said support by said moving con-

tact during movement of said moving contact toward said contact finger.

4. In a circuit interrupter, a contact finger, a support therefor, a moving contact disposed for wiping engagement with said contact finger during movement to the closed circuit position, said contact finger having a predetermined amount of longitudinal and lateral movement with respect to said support, means biasing said contact finger both laterally and longitudinally towards said moving contact, and means carried by said contact finger and said support for moving said contact finger laterally in a direction away from the path of movement of said moving contact in response to longitudinal movement of said contact finger resulting from a positive engagement of said contact finger with said moving contact during movement of the latter to the closed circuit position to break said positive engagement and effect a wiping contact.

5. In a circuit interrupter, a contact structure comprising a cylindrical support member, a plurality of contact fingers disposed adjacent the outer surface of said support member, guide means for maintaining said contact fingers substantially parallel to the longitudinal axis of said support member, said guide means providing limited longitudinal and radial movement of said contact fingers with respect to said support member, a movable operating member extending axially through said support member, a ring contact carried by said operating member the outer surface of which is adapted to make sliding contact with said contact fingers, means biasing said contact fingers into engagement with said ring contact when said operating member is in the closed circuit position, and cam means associated with said contact fingers and said support member for moving said contact fingers radially from said support member in response to longitudinal movement of said contact fingers resulting from positive engagement of said fingers with said ring contact to effect a release of said positive engagement and enable said ring contact to make sliding engagement with said contact fingers.

6. In a circuit interrupter, a quantity of arc extinguishing liquid, separable contacts, actuating means for operating said contacts to the open circuit position for drawing an arc within said liquid, and means actuated by said actuating means and operative in response to predetermined pressure conditions in the region surrounding said contacts for moving a quantity of arc extinguishing liquid which has not been subjected to said arc between said contacts.

7. In a circuit interrupter, an arc chamber having arc extinguishing liquid therein, separable contacts for establishing an arc within said arc chamber, actuating means for operating said contacts, means for moving an additional quantity of arc extinguishing liquid through said arc chamber following arc extinction, energy storing means for operating said liquid moving means following the subsidence of pressure within said arc chamber, and means for operatively connecting said contact actuating means with said energy storing means to cause said actuating means to store energy in said energy storing means during the opening operation of said actuating means.

8. In a circuit interrupter, an arc chamber having arc extinguishing liquid therein, separable contacts for establishing an arc within said arc chamber, actuating means for operating said contacts, piston means for moving an additional

- quantity of an extinguishing liquid through said arc chamber following arc extinction, spring means for operating said piston means, and means for operatively connecting said contact actuating means with said spring means for stressing the latter during the final movement of said actuating means to the open circuit position.
9. In a circuit interrupter, an arc chamber, a quantity of arc extinguishing liquid therein, a stationary contact, a cooperating movable contact, an operating member for moving said movable contact to open and closed positions, means actuated by said operating member during the opening movement thereof to place an additional quantity of arc extinguishing liquid under pressure, and means operative in accordance with predetermined pressure conditions within said arc chamber for causing said additional quantity of liquid to be directed through said arc chamber.
10. In a circuit interrupter, an arc chamber, a quantity of arc extinguishing liquid therein, a stationary contact, a cooperating movable contact, an operating member for moving said movable contact to open and closed positions, pumping means for causing an additional quantity of an extinguishing liquid to flow through said arc chamber, and means coupling said pumping means with said operating member to render said pumping means operative during the opening stroke of said operating member, said coupling means being ineffective to operate said pumping means until predetermined pressure conditions are obtained within said arc chamber.
11. In a circuit breaker, an enclosure, a body of liquid therein, an arc chamber immersed in said liquid, separable contacts at least one of which is movable, an operating member for said movable contact, resilient means for moving said operating member to the open circuit position to establish an arc within said arc chamber, pumping means rendered operative by said resilient means during the opening movement of said operating member for moving a quantity of said liquid through said arc chamber after arc extinction, and means for preventing a reverse flow of liquid from said arc chamber to said pumping means.
12. In a circuit breaker, an enclosure, a body of liquid therein, an arc chamber immersed in said liquid, separable contacts at least one of which is movable, an operating member for said movable contact, resilient means for moving said operating member to the open circuit position to establish an arc within said arc chamber, said enclosure having pressure relieving means including a vent opening and a releasable cover member therefor, said cover member being biased to the closed position by said resilient means, pumping means rendered operative by said resilient means during the opening movement of said operating member for moving a quantity of said liquid through said arc chamber after arc extinction, and means for preventing a reverse flow of liquid from said arc chamber to said pumping means.
13. In a circuit breaker, a housing, a body of liquid in said housing, an arc chamber immersed in said liquid, a stationary contact adjacent one end of said arc chamber, a cooperating movable contact, a plunger for carrying said movable contact, a spring for moving said movable contact into said arc chamber to establish an arc therein and cause liquid to flow longitudinally of the arc stream to assist in extinguishing the arc, means for relieving said housing of pressure produced by said arc including a vent opening and a cover therefor, means operatively coupling said cover with said spring for yieldingly holding said cover in the closed position against the pressure within said housing, and pumping means rendered operative by said spring during movement of said plunger into said arc chamber for moving a quantity of liquid through said chamber, said pumping means being ineffective to move said liquid until the pressure within said arc chamber has been reduced to a predetermined value.
14. In a circuit breaker, an enclosure, a body of liquid therein, an arc chamber immersed in said liquid, separable contacts at least one of which is movable, operating means for actuating said movable contact to the open circuit position to establish an arc in said arc chamber, and means actuated by said operating means during the latter part of its opening movement and operative in response to predetermined pressure conditions in said arc chamber for moving a quantity of said liquid through said arc chamber.
15. In a circuit breaker, an enclosure, a body of liquid therein, an arc chamber immersed in said liquid, separable contacts at least one of which is movable, operating means for actuating said movable contact to the open circuit position to establish an arc in said arc chamber, pumping means for moving a quantity of said liquid through said arc chamber, and means operatively coupling said contact operating means with said pumping means during the final movement of said operating means to its open circuit position for actuating said pumping means, said coupling means enabling said contact operating means to move to its full open circuit position independently of the liquid pumping operation.
16. In a circuit breaker, an enclosure, a body of liquid therein, an arc chamber immersed in said liquid, separable contacts at least one of which is movable, operating means for actuating said movable contact to the open circuit position to establish an arc in said arc chamber, pumping means for moving a quantity of said liquid through said arc chamber following arc extinction, spring means for actuating said pumping means, and means operatively coupling said contact operating means with said spring means during the final movement of said operating means to its open circuit position for storing energy in said spring means, said spring means enabling said contact operating means to move to its full open circuit position independently of the operation of said pumping means.
17. In a circuit interrupter, a support member, a plurality of contact fingers carried by said support member, a contact means movable axially of said contact fingers and adapted to make sliding engagement therewith, said support member having guide means providing limited longitudinal and lateral movement for said contact fingers with respect to the path of movement of said contact means, and means operatively associated with said support and contact fingers for moving said contact fingers laterally in a direction away from said contact means in response to longitudinal movement of said contact fingers resulting from positive engagement of said fingers with said contact means during the closing movement of said contact means to effect release of said positive engagement and enable said contact means to make sliding contact with said contact fingers.
18. In a circuit interrupter, a contact structure comprising a cylindrical support member, a plurality of contact fingers disposed adjacent the

- outer surface of said support member, guide means for maintaining said contact fingers substantially parallel to the longitudinal axis of said support member, said guide means providing limited longitudinal and radial movement of said contact fingers with respect to said support member, a contact member movable axially of said support member and having a contact surface adapted to make sliding contact with said contact fingers, means biasing said contact fingers into engagement with said contact member when said contact member is in the closed circuit position, and means associated with said contact fingers and said supporting member for moving said contact fingers radially from said support member in response to longitudinal movement of said contact fingers resulting from positive engagement of said fingers with said contact member during the closing movement of said contact member to effect a release of said positive engagement and enable said contact member to make sliding engagement with said contact fingers.
19. In a circuit interrupter, an arc chamber having arc extinguishing liquid therein, separable contacts for establishing an arc within said arc chamber, actuating means for actuating said contacts, means for moving an additional quantity of arc extinguishing liquid through said arc chamber, energy storing means for operating said liquid moving means in response to predetermined pressure conditions within said arc chamber, and means for operatively connecting said contact actuating means with said energy storing means to cause said actuating means to store said energy in said energy storing means during the opening operation of said actuating means.
20. In a circuit breaker, a quantity of arc extinguishing liquid, an arc chamber immersed in said liquid, separable contacts at least one of which is movable for establishing an arc in said arc chamber, operating means for said movable contact, means actuated by said operating means for moving a quantity of arc extinguishing liquid into engagement with said arc to aid in extinguishing the arc, additional means for moving arc extinguishing liquid into said arc chamber and means for operatively coupling said additional liquid moving means with said contact operating means at least during the circuit opening movement thereof, said coupling means enabling said contact operating means to move to its full open circuit position independently of the additional liquid moving operation.
21. In a circuit interrupter, a housing containing arc extinguishing liquid and having a vent opening, a closure member for said opening movable to open and closed positions, separable contacts for establishing an arc within said arc extinguishing liquid, liquid moving means operative to cause a flow of arc extinguishing liquid in the path between said contacts, resilient means for biasing said closure member to the closed position and for actuating said liquid moving means, and a second liquid moving means rendered operative by said resilient means for moving an additional quantity of arc extinguishing liquid into the path between said contacts.
22. In a circuit interrupter, a housing containing arc extinguishing liquid, circuit interrupting means within said housing including separable contacts, at least one of which is movable for establishing an arc, liquid moving means operative for subjecting the arc path to a flow of arc extinguishing liquid, pressure relieving means for said housing including a member movable to open and closed positions, single resilient means for actuating said movable contact and said liquid moving means and for biasing said movable member to the closed position against the pressure within said housing, and a second liquid moving means made operative by said resilient means for moving an additional quantity of arc extinguishing liquid into the arc path.
